Primary Examiner — Jae Liang*Assistant Examiner* — Jane Yoon(57) **CLAIM**

The ornamental design for a laptop bag, as shown and described.

DESCRIPTION

FIG. 1 is a perspective view of a laptop bag in an open position, showing the new design;
 FIG. 2 is another perspective view thereof;
 FIG. 3 is another perspective view thereof;
 FIG. 4 is a front elevation view thereof;
 FIG. 5 is a back elevation view thereof;
 FIG. 6 is a left-side view thereof;
 FIG. 7 is a right-side view thereof;
 FIG. 8 is a top plan view thereof; and
 FIG. 9 is a bottom plan view thereof.

FIG. 10 is a perspective view of the laptop bag of FIG. 1 in a closed position;
 FIG. 11 is another perspective view thereof;

FIG. 12 is an enlarged view of the encircled portion '12' in FIG. 10;

FIG. 13 is an enlarged view of the encircled portion '13' in FIG. 1; and,

FIG. 14 is an enlarged view of the encircled portion '14' in FIG. 10.

The equal-length broken lines depict portions of the Laptop Bag that form no part of the claimed design.

The dash-dot lines in FIGS. 1, 10, 12, 13, and 14 illustrate the boundaries of the enlarged view indicators and form no part of the claimed design.

1 Claim, 14 Drawing Sheets
